BLADE HOLDER

Application filed June 27, 1927. Serial No. 201,638.

Our invention appertains to holding devices for razor blades. A safety razor blade is very useful as a knife if it is provided with a suitable handle whereby it may be held in the hand.

5 An important object of our invention is to provide a razor blade handle which may be made at the cost of less than one cent, but nevertheless will possess certain characteristics which will render it very handy.

10 It is an object of the invention to provide a razor blade holder which is formed from one piece.

15 Another object of the invention is to provide a holder in which the blade is locked to it by manipulation.

20 A further object of the invention is to provide a blade holder of the character mentioned in which the blade may be readily placed and removed.

25 In the following description the preferred form of our invention will be described. It is not our intention to thereby limit ourselves to the one embodiment, but intend that our protection shall extend to the various 30 embodiments in which the invention may be included.

The invention will be described with reference to the accompanying drawing in which:

35 Fig. 1 is a perspective view showing the holder supporting a razor blade.

40 Fig. 2 is a view similar to Fig. 1, but showing the holder before the ends are moved into locked position.

45 Fig. 3 is a perspective view showing the holder per se before the blade has been installed therein.

50 Fig. 4 is a section taken on the line 4—4 of Fig. 1.

Our invention has a metal strip 11 which preferably has the characteristic of spring-metal and may be phosphor bronze. This strip 11 is bent at 12 so that the primary 55 end 13 and the secondary end 14 thereof extend parallel and adjacent to each other, as illustrated in Fig. 3. The primary end 13 is provided with a pair of outstruckears 15. The outstruckears 15 have portions 17 60 which project substantially perpendicular to

the primary end 13 and serve as a centralizing means. At the outer ends of these portions 17 are engagers 18 which serve as an engaging means of the invention. The engagers 18 extend substantially parallel to the primary end 13. The numeral 20 represents a razor blade which is to be supported, as shown in Figs. 1 and 2, by the holder. The razor blade 20 is of the type of blade made for use in Gillette razors and has openings 21 formed therein. The centralizing means 15 extend through two of the openings 21, as illustrated in Figs. 1 and 2, so that the outer end of the blade projects beyond the primary and secondary ends. 65 The blade is wider than the strip 11 so that the cutting edge 22 of the blade rests below the lower edge of the strip 11. As shown, the secondary end 14 has an opening 23 to which a slot 24 is connected; and a recess 25 70 to which a straight end 26 is connected at the end thereof. After the blade has been installed on the primary end 13 so that the centralizing means 15 extend through two of the openings 21 thereof, the secondary end 75 14 is moved from the position shown in Fig. 3 into the position shown in Fig. 2. At this time one of the ears or engagers 18 has extended through the opening 23, and the other has passed through the recess 25 so that they 80 both rest in planes outside the secondary end 14. The next operation is to slide the secondary end 14 upward relative to the primary end 13 so that the opening 23 and recess 25 are disaligned from the engagers 85 18. After this manipulation the engagers 18 will extend around portions 27 and 28 which are adjacent to the face 26 and the slot 24, thus preventing the primary and secondary ends from moving outward relative to each 90 other. The locking means, just described, will hold the blade to the holder so that it may be used as a knife. In order to prevent the blade from twisting when used under pressure, we provide a thrust-flange 95 29 which extends above and may be engaged by an upper edge 30 of the blade.

It will be seen that if the secondary end 14 is moved downward relative to the primary end 13 the ends are free to separate 100

and the blade would then be released. In order to prevent this inadvertent unlocking of the blade 20 from the handle we provide a latch means which includes a latch arm 33 which is formed at the upper edge of the secondary end 14 between recesses 34. The upper end of the latch arm 33 is provided with a projection 35 which is formed by crimping the end thereof. The upper portion of the primary end 13 which is adjacent to the latch arm 33 is provided with a slit so as to form a strip 36. This strip is outbent as shown so as to provide a lug 37. When the secondary end 14 is slid upward relative to the primary end 13 the parts of these ends must be held in close contact, preferably by squeezing the two ends together with the fingers so that the latch arm 33 may pass below the lug 37. When the parts have been moved into the position shown in Figs. 1 and 2 and the ends released, the primary and secondary ends will tend to move away from each other in the plane of the latch means so that the latch arm 33 moves away from the primary end 13 and engages the outer part of the lug 37. The end 35 of the latch arm at this time moves into the position shown in Fig. 4 and prevents a relative sliding movement between the primary and secondary ends. This latch means retains the two ends in the position shown until they are pressed together, as indicated by dotted lines 40 in Fig. 4, which will permit the end 35 of the latch arm 33 to move downward inside the lug 37.

The invention also provides a means for preventing the primary and secondary ends from moving longitudinally with respect to each other when the holder is in latched position as shown in Fig. 1. This means comprises a notch 41 formed in the upper edge of the secondary strip into which an ear 42 formed at the upper end of the primary strip extends when the parts are in the position shown. The engagement of the ear in the notch prevents this longitudinal movement.

As previously pointed out, we do not wish to be limited to the particular form of holder illustrated in the drawing. It is possible to make holders on the same principle but being in a slightly different design. For example, with little re-designing it is possible to eliminate the latch for latching the primary and secondary ends in a locked position. It is also possible by a simple rearrangement of parts to shift the blade 20 into position at right angles to that shown in the drawing so that the blade may be used as a scraper.

A very important part of the invention is that it is made in one piece. The strip 11 when being formed is flat and may be made by a single stamping operation. This is

very important since it makes it possible to provide a blade holder very cheaply. Even when making the holders in small lots, they cost less than one cent each. Another very important part of the invention is the means for locking the primary and secondary ends of the strip together. These two ends are locked together by manipulation which consists in merely sliding the two ends relative to each other. This is much simpler than attaching the two ends together by use of a separate securing means.

The latch means provided by the invention is very important although not indispensable, because it holds the two ends in locked position so that they cannot inadvertently be slid relative to each other and the blade released.

We claim as our invention:

A holder for supporting a razor blade with one edge thereof in exposed operative position, said holder comprising a strip of resilient metal bent upon itself to form a handle, the outer ends of the strip forming blade holding members, means for holding the members together with a razor blade therebetween, said means comprising an integral hooked ear on one of said members, the other of said members having a slot therein, the hooked end of the ear being adapted to pass through the aperture of the razor blade and the slot and engage over the last named member and a projection extending from the upper edge of one of said members and a lug formed on the upper edge of the other member, said projection and lug being adapted to interlock to prevent relative upward sliding movement of the members beyond operative blade holding position.

In testimony whereof, we have hereunto set our hands at Los Angeles, California, this 22nd day of June, 1927.

ETHEL F. WHITE.
